Patented Jan. 26, 1926.

UNITED STATES PATENT OFFICE.

WILLIAM J. LUTTON, OF PATERSON, NEW JERSEY, ASSIGNOR OF ONE-HALF TO
MAURICE FRANCK, OF PATERSON, NEW JERSEY.

PATTERN MECHANISM FOR LOOMS.

Application filed April 14, 1924. Serial No. 706,457.

To all whom it may concern:

Be it known that I, WILLIAM J. LUTTON, a citizen of the United States, and resident of Paterson, in the county of Passaic and State of New Jersey, have invented a new and useful Improvement in Pattern Mechanism for Looms, of which the following is a specification.

This invention relates to a pattern mechanism for looms and more particularly to a supplemental mechanism adapted to be combined with a shuttle box pattern chain mechanism and a multiplier chain mechanism of well known construction and operation, which supplemental mechanism will present certain novel features of construction, form and arrangement, whereby the movement of the shuttle boxes with respect to each other may be accurately timed to suit various requirements and for producing various patterns of weaves.

A further object is to provide a mechanism of the above character which will be comparatively simple and inexpensive to manufacture and which may be readily applied to looms now in common use.

I have only shown in the drawings detached portions of a shuttle box pattern chain mechanism, and a multiplier chain mechanism of well known construction and operation, both of which mechanisms are particularly shown and described in United States Letters Patent No. 917,088 dated April 6, 1909, with my improvements combined therewith.

A practical embodiment of my invention is represented in the accompanying drawings, in which—

Fig. 1 represents a side elevation of a portion of a loom having my improved structure applied thereto.

Fig. 2 represents a detail vertical section taken inside the frame of the parts shown in Fig. 1, looking in the opposite direction.

Fig. 3 represents a detail vertical section taken in the plane of the line III—III of Fig. 2, looking in the direction of the arrows.

Fig. 4 represents a similar view with the parts shown in another position, and

Fig. 5 represents an enlarged detail view of the driving cylinder, with the parts in the position as shown in Figs. 1 to 3 inclusive.

The frame of the loom is denoted by 1,

the flexible connections by 2, which connections are arranged to control the movement of the drop boxes (not shown), and the oscillating levers by 3. The vibrating levers 4 are each provided with a mutilated gear 5 loosely mounted thereon and an arm 6, which arm connects the gear with its oscillating lever 3.

The pattern chain supporting wheels (not shown) are rotated with a shaft 7, which is provided with a spur gear 8 arranged to mesh with a pinion 9 carried by a shaft 10.

A mutilated cylinder gear 11 fast on the shaft 10 is arranged to coact with the mutilated gears 5, and a similar mutilated gear 12, fixed on shaft 13 also coacts with the mutilated gears 5. The mutilated cylinder 11 is driven from a vertical shaft 14 through mitre gears 15, 16, while the mutilated cylinder gear 12 receives its motion from the vertical shaft 14 by means of mitre gears 17, 18.

The parts to which I have thus briefly alluded are well known in the art, combined and arranged substantially as shown and it is not thought necessary to give a detail statement of their operation, since the same is well known to those skilled in the art, my present invention pertaining to certain means for controlling the operation of the above named parts in order to multiply the effect of a supplemental shuttle box pattern chain on the pattern chain, thereby shortening the length of chain normally or previously required to produce a certain pattern, and reducing the weight and friction of the parts.

The shuttle box pattern chain mechanism comprises a cylinder 19 fast on a sleeve 20, which is mounted to rotate on the shaft 7. The cylinder 19 is provided with a box pattern chain 21, made up of links 22, short bars 23 and long bars 24. One side of this chain carries mutilated rolls 25 arranged to engage a shoe 25* carried by a lever 26 pivoted on a shaft 27 mounted in the frame 1. This lever 26 is connected to a bell crank lever 26*, which controls the movement of the box pattern chain 21, by a link 28, as shown in Fig. 2. The multiplier pattern chain cylinder denoted by 122 is mounted to rotate on the shaft 7 and carries a chain 123, composed of links and bars, supporting rolls and tubes in the usual manner. The cylinder 122 has a star-wheel 124 which is oper-

ated by a pinwheel 125 splined on a shaft 126 driven from the shaft 10 by means of a gear 127 fast thereon and a gear 128 fixed to the shaft 126. The rolls 129 and the chain 123 are arranged to engage an indicator lever 130 pivoted at 131, which lever is connected to a bell crank lever 132 by a link 133, as shown in Fig. 1. This bell crank lever 132 is associated with mechanism (not shown) for moving the pinwheel 125. A similar star-wheel and pinwheel mechanism (not shown) for actuating the box pattern chain 21, is mounted adjacent the star-wheel 124 and pinwheel 125 respectively, and arranged to be operated by means (not shown) connected with the bell crank lever 26*. This multiplier chain mechanism is particularly described and claimed in United States Letters Patent No. 917,088 dated April 6, 1909, also shown and described in my co-pending application Serial No. 659,760, filed August 28th, 1923, and I deem it necessary to only show and describe such parts of said mechanism as will give a clear understanding of the application of my present invention thereto.

I will now describe my improvements combined with the parts above referred to.

A supplemental shuttle box pattern chain mechanism is mounted in suitable bearings in the frame and comprises a cylinder 29 provided with a pattern chain made up of links 30, 31, bars 32, rollers 33 and tubes 34. The cylinder 29 is fast on a shaft 35 journaled in the frame, which shaft receives its motion from the shaft 7 through the spur gear 8 fixed thereon and a spur gear 36 fast on the shaft 35. The chain is also supported on an idler 37 loosely mounted on a shaft 38, the ends of which shaft are secured in brackets 39, 40 carried by the frame 1. The shaft 38 may be adjusted vertically in slots 41, 42 in the brackets 39, 40, thereby allowing a vertical adjustment for the chain. Extending over this chain is a series of levers 43 pivotally supported at one end on a shaft 44 carried by the frame 1, which levers, in the revolution of the chain, are adapted to be engaged by the rollers 33 and lifted thereby. Each of the levers 43 is connected to its vibrating lever 4, immediately below, by a link 45, so that as the lever is raised by the roller passing thereunder, the vibrating lever will be actuated and its respective shuttle brought into action in the usual manner. The levers 43 are maintained in position and arranged to oscillate in a guide 46 carried by the frame 1.

Means have also been provided for moving the supplemental shuttle box pattern chain laterally to bring the rollers or tubes, in the same lateral plane, under the levers 43, which means comprises a cradle 47 provided with vertically disposed side walls 48. This cradle is secured to a bar 49, which is ar-

ranged to be reciprocated in the bracket 39 and a bracket 50 carried by the frame 1. Motion is imparted to the bar 49 by means of a bell crank lever 51 pivoted at 52 in a bracket 53, one end of which the bell crank lever 51 is connected to an ear 54 uprising through an oscillatable lever 55. One end of this lever 55 is fulcrumed on the shaft 27 and the other end provided with a shoe 56 which is adapted to be engaged by the long bars 24 of the shuttle box pattern chain 21. A helically coiled retraction spring 57 is attached at one end to a pin 58, which pin forms the fulcrum of the bar 49 and bell crank lever 51, and its other end to the bracket 39, so that the cradle and chain will be normally held in one position by the spring and moved to the other position by the coaction of the long bars 24 with the shoe 56 and its adjacent mechanism.

In order that the supplemental chain may be rotated in a direct path, I provide each bar 32 with a pair of guides, in the form of washers 59, 60. The washers 59 are arranged to enter and recede from an annular groove 61 formed in a sleeve 62 loosely mounted on the shaft 35. The chain is further kept in alinement by reason of the links 31 being disposed obliquely with respect to each other, while the links 30 are located in parallelism with each other.

Thus it will be seen that by the arrangement of the rollers and tubes on the bars of the supplemental shuttle box pattern chain and the lateral movement of the chain, different combinations of rollers and tubes may be brought under the levers 43, thereby materially increasing the range of operation to which the levers and their adjacent mechanism may be placed, as well as reducing the length of chain required to produce the desired pattern.

It will therefore be understood from the foregoing, that each of the levers 43 will be actuated by one or the other set of rollers 33 and tubes 34 arranged in alinement on the supplemental shuttle box pattern chain as the chain is moved on its cylinder 29.

The operation of my improvement in connection with the shuttle box pattern chain and multiplier pattern chain mechanisms, will be readily understood by those skilled in the art, and briefly is as follows:—

When the pinwheel is in engagement with the star-wheel of the box pattern chain 21, this pattern chain will be rotated until one of the mutilated rolls 25 on the chain 21 comes under the shoe 25*, the movement of which lifts the lever 26. The raising of this lever 26, actuates the bell crank lever 26*, through the link 28, so as to disengage the pinwheel and star-wheel of the box pattern chain 21. Simultaneously with the disengagement of the pinwheel and star-wheel of the box pattern chain 21, the pinwheel 125 is 130

5 moved into mesh with the star-wheel 124, thereby setting the multiplier pattern chain 123 in motion. During the revolution of the multiplier pattern chain 123, the box pattern chain 21 may remain stationary until the next roll 129 on the multiplier pattern chain comes under and actuates the indicator lever 130. The movement of the indicator lever 130 will rock the bell crank lever 132, 10 through the link 133 and thereby actuate the mechanism to move the pinwheel 125 away from the star-wheel 124, placing the multiplier pattern chain 123 at rest. Simultaneously with the movement of the pinwheel 125, the star-wheel of the box pattern chain 21 was engaged by its coacting pinwheel thereby setting the box pattern chain 21 in motion.

15 During the revolution of the shuttle box pattern chain 21 the extended or long bars 24 will be brought into engagement with the shoe 56 of the lever 55 which will be lifted and cause the bell crank lever 51 to be rocked, which in turn will actuate the bar 49 carrying the cradle 47. In the movement of this cradle 47 the upwardly extending side walls 48 will be caused to engage the pins 32 of the chain and move the chain laterally, thereby causing the set rollers and tubes, operating the levers 43, as shown in Fig. 3, to pass therefrom and the adjacent set of rollers and tubes to move under the levers and actuate the shuttles through the links 45, vibrators 4 and their adjacent mechanism.

20 It will be understood that the rollers and tubes are so arranged with respect to the long bars 24 that the movement of the chain will always take place when the rollers and tubes under the levers 43 are equal in height or paired.

25 As the long bar 24 passes from its engagement with the shoe 56 the spring 57 will exert a pull upon the pin 58 and return the bar 49 with its cradle and chain to their normal position and since there is no pin to engage the shoe 56, the bell crank lever 51 and rocking lever 55 will be returned to their position as shown in Figs. 50 1 to 3 inclusive.

30 The advantages of my improvements will be readily perceived by those skilled in the art, and may be easily applied to box pattern chain and multiplier chain mechanisms 35 of ordinary and well known construction.

35 I desire it to be understood that various changes may be resorted to in the form, construction and arrangement of the several parts without departing from the spirit and scope of my invention; hence, I do not intend to be limited to the details herein shown and described, except as they may be included in the claims.

40 What I claim is:—

45 1. In a pattern mechanism for looms, the

combination with a shuttle box pattern chain, a multiplier pattern chain, mechanism coacting with said chains to control the movement of the chains, and vibrating levers, of a supplemental shuttle box pattern chain, means connected to the vibrating levers and actuated by the supplemental shuttle box pattern chain for controlling the movement of the vibrating levers, and mechanism for moving said last named chain laterally to present different surfaces of the chain to said means for actuating the vibrating levers.

2. In a pattern mechanism for looms, the combination with a shuttle box pattern chain, a multiplier pattern chain, mechanism coacting with said chains to control the movement of the chains, and vibrating levers, of a supplemental shuttle box pattern chain, means connected to the vibrating levers and actuated by the supplemental shuttle box pattern chain for controlling the movement of the vibrating levers, and mechanism for moving said last named chain laterally in one direction to present different surfaces of the chain to said means for actuating the vibrating levers.

3. In a pattern mechanism for looms, the combination with a shuttle box pattern chain, a multiplier pattern chain, mechanism coacting with said chains to control the movement of the chains, and vibrating levers, of a supplemental shuttle box pattern chain, means connected to the vibrating levers and actuated by the supplemental shuttle box pattern chain for controlling the movement of the vibrating levers, mechanism for moving said last named chain laterally in one direction, and a spring actuated means for moving the chain in the other direction to present different surfaces of the chain to said means for actuating the vibrating levers.

4. In a pattern mechanism for looms, the combination with a shuttle box pattern chain, a multiplier pattern chain, mechanism coacting with said chains to control the movement of the chains, and vibrating levers, of a supplemental shuttle box pattern chain, means connected to the vibrating levers and actuated by the supplemental shuttle box pattern chain for controlling the movement of the vibrating levers, and mechanism for moving said last named chain laterally to present different surfaces of the chain to said means for actuating the vibrating levers, said mechanism being actuated by the shuttle box pattern chain.

5. In a pattern mechanism for looms, the combination with a shuttle box pattern chain, a multiplier pattern chain, mechanism coacting with said chains to control the movement of the chains, and vibrating levers, of a supplemental shuttle box pattern chain, means connected to the vibrat-

ing levers and actuated by the supplemental shuttle box pattern chain for controlling the movement of the vibrating levers, and mechanism for moving said last named chain laterally in one direction to present different surfaces of the chain to said means for actuating the vibrating levers, said mechanism being actuated by the shuttle box pattern chain.

with and connected to the vibrating levers, and mechanism for moving said last named chain laterally, said mechanism actuated by the shuttle box pattern chain.

11. In a pattern mechanism for looms, the combination with a shuttle box pattern chain, a multiplier pattern chain, mechanism coacting with said chains to control the movement of the chains, and vibrating levers, of a supplemental shuttle box pattern chain, rocking levers coacting therewith and connected to the vibrating levers, and mechanism for moving said last named chain laterally in one direction, said mechanism actuated by the shuttle box pattern chain. 70 75 80

12. In a pattern mechanism for looms, the combination with a shuttle box pattern chain, a multiplier pattern chain, mechanism coacting with said chains to control the movement of the chains, and vibrating levers, of a supplemental shuttle box pattern chain, rocking levers coacting therewith and connected to the vibrating levers, mechanism for moving said last named chain laterally in one direction, said mechanism actuated by the shuttle box pattern chain, and a spring actuated means for moving the chain in the other direction.

13. In a pattern mechanism for looms, 95
the combination with a shuttle box pattern
chain, a multiplier pattern chain, mechanism
coacting with said chains to control
the movement of the chains, and vibrating
levers, of a supplemental shuttle box pat- 100
tern chain, means connected to the vibrating
levers and actuated by the supplemental
shuttle box pattern chain for controlling
the movement of the vibrating levers, mech- 105
anism for moving said last named chain,
said mechanism comprising a rocking lever
adapted to be engaged by the shuttle box
pattern chain, a reciprocating bar, a bell
crank lever connecting said bar and rock- 110
ing lever, and means on the bar engaging
the chain for moving it laterally.

14. In a pattern mechanism for looms, the combination with a shuttle box pattern chain, a multiplier pattern chain, mechanism coacting with said chains to control the movement of the chains, and vibrating levers, of a supplemental shuttle box pattern chain, means connected to the vibrating levers and actuated by the supplemental shuttle box pattern chain for controlling the movement of the vibrating levers, mechanism for moving said last named chain, said mechanism comprising a rocking lever adapted to be engaged by the shuttle box pattern chain, a reciprocating bar, a bell crank lever connecting said bar and rocking lever, means on the bar engaging the chain for moving it laterally in one direction, and a spring actuated means for moving the chain in the other direction. 115 120 125 130

15. In a pattern mechanism for looms, the combination with a shuttle box pattern chain, a multiplier pattern chain, mechanism coacting with said chains to control the movement of the chains, and vibrating levers, of a supplemental shuttle box pattern chain, means connected to the vibrating levers and actuated by the supplemental shuttle box pattern chain for controlling the movement of the vibrating levers, mechanism for moving said last named chain, said mechanism comprising a rocking lever adapted to be engaged by the shuttle box pattern chain, a reciprocating bar, a bell crank lever connecting said bar and rocking lever, a cradle on the bar engaging the chain for moving it laterally in one direction, and a spring actuated means for moving the chain in the other direction.
16. In a pattern mechanism for looms, the combination with a shuttle box pattern chain, a multiplier pattern chain, mechanism coacting with said chains to control
- the movement of the chains, and vibrating levers, of a supplemental shuttle box pattern chain, means connected to the vibrating levers and actuated by the supplemental shuttle box pattern chain for controlling the movement of the vibrating levers, mechanism for moving said last named chain, said mechanism comprising a rocking lever adapted to be engaged by the shuttle box pattern chain, a reciprocating bar, a bell crank lever connecting said bar and rocking lever, a cradle on the bar engaging the chain for moving it laterally in one direction, and a spring actuated means for moving the chain in the other direction.
17. In testimony that I claim the foregoing as my invention, I have signed my name this fifth day of April, 1924.

WILLIAM J. LUTTON.
